H. W. TWYMAN,
ILLUMINATED SIGN, FACIES, AND THE LIKE,
APPLICATION FILED JUNE 22, 1920.

1,385,764.

Patented July 26, 1921.

UNITED STATES PATENT OFFICE.

HAROLD WILLIAM TWYMAN, OF NORBURY, LONDON, ENGLAND.

ILLUMINATED SIGN, FACIES, AND THE LIKE.

1,385,764.

Specification of Letters Patent. Patented July 26, 1921.

Application filed June 22, 1920. Serial No. 390,763.

To all whom it may concern:

Be it known that I, HAROLD WILLIAM TWYMAN, a subject of His Majesty the King of England, and resident of Norbury, in the county of London, Kingdom of England, have invented certain new and useful Improvements in Illuminated Signs, Facies, and the like, of which the following is a specification.

10 This invention relates to improvements in illuminated signs, advertisements and the like of the kind in which two movable multi-colored screens, in the form of an endless band or bands, are caused to travel relatively to one another in parallel planes between the source of light and the transparency or sign to be illuminated so as to produce varied colored effects.

Now according to the present invention 20 the screens used are formed of colored open-mesh material adapted to give simultaneously almost infinite variations of color and (or) markings as of watered silk, the combination giving the whole a somewhat iridescent effect. The screens may also preferably be arranged around vertical rollers enabling a sign to be provided having two or more illuminated sides.

In carrying the invention into practical 30 effect the device may conveniently comprise a box or casing having one or more sides uniformly illuminated.

The sides of the box not illuminated are 35 preferably painted dead black or coated with any suitable non-reflecting material. The characters forming the sign are suitably either stenciled in metal or other suitable material or left transparent on an opaque background or made opaque on a transparent background. When more than one side is 40 to be illuminated, between the source or sources of light and the illuminated sides of the box or case conveniently two thicknesses of colored open-square-mesh material may 45 be caused to move laterally in parallel planes in two concentric endless bands moving parallel to the illuminated sides at slightly differing rates of speed, by means of rollers or spindles. Between the opposite illuminated 50 double thicknesses of open-square-mesh material is a dividing wall or partition painted black, or coated with any suitable non-reflecting material. When one side only 55 is to be illuminated, between the source or sources of light and the illuminated side of the box or case conveniently two thicknesses

of colored open-square-mesh material may be caused to move laterally in parallel planes in one endless band moving parallel to the illuminated side by means of rollers or spindles. The inner side of the endless band may be brought into the necessary adjustment with the outer side by means of rods or guides. 60

In order that my said invention may be 65 more clearly understood and more readily carried into effect it is hereinafter described with reference to the accompanying sheet of drawings in which:

Figure 1 is a front elevation of an advertising sign having more than one side illuminated; 70

Fig. 2 is a section on the line 2-2 of Fig. 1;

Fig. 3 is a plan;

Fig. 4 is a plan of a sign having only one side illuminated, and 75

Fig. 5 is a section on the line 5-5 of Fig. 4.

As shown the improved sign comprises 80 sides *b* stenciled or painted to leave the characters *b'* of the sign transparent on an opaque ground or opaque on a transparent ground.

The source or sources of light *c* would 85 preferably be arranged in such a position that direct rays are not visible through the transparent characters *b'* and behind the colored material *d* from the spectator's point of view. In a sign having more than one 90 side illuminated as in Figs. 1 to 3, on four vertically arranged outer rollers or spindles *e* would be mounted an endless band *d* of suitably colored open-square-mesh material, such as silk, voile, organdy, leno, muslin, or 95 gauze. On four inner rollers or spindles *f* would be mounted a second endless band *d'* of the same material, and having the same size mesh. Both these bands *d* *d'* would be caused to move laterally at slightly different 100 rates of speed by means of an electric motor *g*, or similar source of power and belting or gearing *h* shown diagrammatically in the drawings. Between the opposite illuminated double thicknesses of material *d* *d'* 105 and parallel with same would be placed a dividing wall or partition *i*, painted black or coated with any suitable non-reflecting material, forming a non-reflecting background to the same. The open-square- 110 mesh material *d*, *d'* would be colored, with one or more colors, in the latter case being

covered with either geometric patterns or irregular splotches of various colors.

The device could be used as a sign for advertising or similar purposes. When illuminated from within in the manner described, the effect to the spectator is that of a constantly blending variety of colors, with simultaneous constantly moving striated markings as of watered silk in almost infinite variety.

In a sign where only one side is required to be illuminated as in Figs. 4 and 5 only one endless band *d* of open-square-mesh material would be employed, the inner side of which would move in parallel planes with, but in the opposite direction to, the outer side as will be readily understood. The inner side of the band would be brought into the necessary proximity to the outer side in order to obtain the necessary striated or water-mark effect by rods or guides *j* as shown. The unilluminated sides of the box would be painted black or coated with any suitable non-reflecting material and the source or sources of light *c* also placed out of the direct line of vision of the spectator as previously described. It is not essential to this invention to use belting or gearing *h* for driving the rollers or spindles *e* as any source of power and any suitable form of transmission may be employed.

The source or sources of light are placed in such position with regard to the placing of the sign that direct rays are not visible behind the stenciled or transparent portions of the sign or in the spectator's line of vision.

The dividing wall or partition *i* would only run longitudinally down the center

where two sides only are to be illuminated 40 as in Figs. 1 and 3. Where it is desired to illuminate three or four sides this partition would be varied in shape so as to suit the area covered by the lettering of the sign and by the arrangement of the interior lighting 45 as will be readily understood.

It will be seen that when the two bands are stationary and slightly spaced from each other the novel iridescent and watered silk effect will be obtained as the observer passes 50 in front of the device due to changing viewpoint.

What I claim is:—

1. An advertising and display apparatus including a transparent character bearing 55 section, a source of light and a plurality of independent colored screens moving in parallel planes and at different rates of speed and between said source of light and character bearing section.

2. An advertising and display apparatus including a transparent character bearing section, a source of light and a plurality of independent colored screens moving in parallel planes between said source of light and character bearing section, and a non-reflecting back ground.

3. An illuminated advertising and display apparatus including a character bearing transparent section, a source of light 70 and a plurality of fabric screens interposed between the source of light and character bearing section and moving in opposite directions at different rates of speed and in parallel planes.

In testimony whereof I have hereunto signed my name.

HAROLD WILLIAM TWYMAN.
